UNITED STATES PATENT OFFICE.

ALBERT H. DANIELS AND ALMON B. ROWELL, OF MANCHESTER, NEW HAMPSHIRE.

BILL-HOLDER.

SPECIFICATION forming part of Letters Patent No. 367,274, dated July 26, 1867.

Application filed December 17, 1866. Serial No. 221,885. (No model.)

To all whom it may concern:

Be it known that we, ALBERT H. DANIELS and ALMON B. ROWELL, citizens of the United States, residing at Manchester, in the county 5 of Hillsborough and State of New Hampshire, have invented certain new and useful Improvements in Bill-Holders; and we do hereby declare the following to be a full, clear, and exact description of the invention, such as will 10 enable others skilled in the art to which it appertains to make and use the same.

This invention relates to an improvement in bill or paper holders, the object thereof being to provide a holder or file which will not 15 loosen its grasp upon the papers already contained within it while additional ones are being inserted; and the invention consists in the construction, arrangement, and combination of parts, substantially as will be hereinafter 20 described and claimed.

In the annexed drawings, illustrating our invention, Figure 1 is a front elevation of our improved bill-holder or file in its suspended position, and shows the arrangement of papers 25 in the file. Fig. 2 is a side elevation of the same with no papers placed therein. Fig. 3 is a vertical cross-section showing the disposition of the parts when papers are being inserted, and at the beginning of the insertion. Fig. 30 4 is a similar section showing a paper or bill when about to take the position which it permanently occupies when in the holder; and Fig. 5 is a section showing the position of the parts when papers are being removed.

Like letters of reference denote corresponding parts throughout the several figures.

A represents the base or bottom board of the holder, which is perforated in its upper portion or otherwise suitably constructed to adapt 40 it to be hung upon a wall or other support. The base A, and consequently the parts carried thereby, may be hung vertically against the supporting object or may rest horizontally upon it, accordingly as either location best 45 suits the convenience of the user. In the drawings we have assumed that the holder is hung vertically against its support.

The devices for securely holding papers, bills, letters, cards, memoranda, and other slips 50 against the base-board consist, essentially, of two parallel holder-bars arranged across the

face of said board and movable laterally toward and away from it.

B represents the lower, and C the upper, of these two holder-bars. The bar B is carried 55 by the vertical spring-rods D D, to the upper extremities of which it is firmly attached, the lower extremities of the spring-rods being secured to the base-board A. The springs D D force the bar B against the board, and hence 60 when papers, &c., are placed between it and the board they will be closely confined.

A short distance above the bar B the board A is provided with a broad shallow groove, a, which at certain times during the operation 65 of placing papers within our improved file serves to receive the upper holder-bar, C. The holder-bar C is formed with an inclined face, which presents itself toward the bar B, the lower edge of bar C being made sharp in consequence of this construction.

E E designate curved arms or levers, which are pivotally connected near their middle points to the opposite ends of the holder-bar C. The upper ends of the arms E E are connected together by a cross-piece, F, which serves as a handle, while the lower portions of said arms are provided with curved slots e, which inclose projecting pins b on the ends of the holder-bar B. Further, there are links or 80 braces G G, arranged near each vertical edge of the board A, which are pivotally connected with the ends of the bar C, the same projections, screws, or pins, c c, on said bar serving as pivots for the curved arms and for the links. 85 The lower ends of the links are pivoted to suitable projections, as d, on the board A. A short wire spring, k, fastened to the bar C and passed through a perforation in one of the side arms, E, serves to keep the bar C from being 90 displaced from its true relative position.

The operation of placing papers, &c., in a bill holder or file thus constructed is as follows: Suppose the parts of the device to be in the position shown in Figs. 1 and 2, with the 95 edge of holder C resting in the groove a, slightly below the surface of the board. When it is desired to place a paper in the holder, the user will grasp the handle F and press it toward the board A. The pivots c c will serve as fulcra for the arms E E, which will now act as levers to raise the bar B from the board by

overcoming the elastic force of the springs D D. The letter or paper may now be placed between the bar B and the board and pushed upward until its upper end rides up the inclined face of bar C, and is limited in its movement by some suitable stop, as H, which is fastened to the board. (See Fig. 3.) If, now, the pressure on the handle F be relaxed, the bar B will be returned close to the board, thus binding the inserted paper tightly between itself and the board, and as the handle falls or is moved downward, as shown in Fig. 4, that portion of the letter which rested on the inclined face of bar C will be permitted to fly behind said bar and between it and the board. 15 When the handle descends, the arms E E will obviously move, so that the pins b b will be placed in the ends of the curved slots opposite what they were before, as shown in Fig. 5. 20 When it is desired to insert another slip, the handle will again be lifted to the position shown in Fig. 1 and again pressed toward the board A. This time the bar C, upon whose ends are the fulera for the levers E E, will bear upon the previously-inserted paper or papers while the bar B is being raised for the admission of the next. Therefore papers can never slip from the file while others are being placed in it. 25 30 When the user desires to remove papers, he simply throws the handle downward, if it be not down already, and continuing the downward pressure thereupon, as seen in Fig. 5, causes the bar B to be drawn away from the board. The bar C being already at a distance 35 from the board, neither of the holder-bars can exert any retaining-pressure upon the papers, and they may be freely removed. The papers can be returned in a bunch to the holder by 40 lifting the bars in the same manner as required to remove them.

Having thus described our invention, what we claim as new, and desire to secure by Letters Patent, is—

45 1. In a bill holder, two parallel holder-bars connected and arranged together, and in combination with a base-board, spring-rods, and operating-handle, so that the papers may be held firmly at all times, those previously in-

serted being held securely during the addition 50 of others, substantially as described.

2. The combination of the base-board, the lower holder-bar, the springs whereby said bar is supported and forced against the face of the board, the upper holder-bar, the curved 55 levers pivoted to the upper bar and slotted to embrace projecting pins on the lower bar, and the connecting-handle between the levers, all arranged and operated substantially as shown and described.

3. The combination of the base-board, the lower holder-bar carried by spring-rods secured to said board, the upper holder-bar having the face adjacent to the lower bar inclined, the curved levers pivoted to the upper bar and slotted to embrace projecting pins on the lower 65 bar, and the bracing-links pivoted at one end to the extremities of the upper bar and at the lower end upon the base board, substantially as described.

4. The combination of the base-board having a projecting stop and a transverse groove, the inclined-faced upper holder-bar adapted to rest its lower edge in said groove, the lower holder-bar held by springs against the face of 75 the board, the slotted and curved connecting-levers, and the operating-handle, substantially as shown and described.

5. The combination of the base-board, the lower holder-bar held against the face of the 80 board by springs, and the arms or levers pivotally connected with the extremities of the upper bar, and likewise with the extremities of the lower bar, substantially as described.

6. The combination of the base board, the 85 lower holder-bar carried by springs secured to said board, the upper holder-bar, the slotted and pivoted connecting-levers, the operating-handle, and the pivoted bracing-links, all arranged substantially as shown and described. 90

In testimony whereof we affix our signatures in presence of two witnesses.
